SHOE WITH INSOLE EXPOSABLE TO VIEW

Jervis H. Sloan, St. Louis, and Marian H. Gilkerson, Chesterfield, Mo.

Application September 1, 1950, Serial No. 182,784

4 Claims. (Cl. 36—8.4)

1

This invention relates to uppers for all types of shoes, and more particularly to the form of the upper and its tongue portion and their relation one to the other, and this especially when considering the purpose in view, namely, of making it possible to inspect, when desired, the entire shoe insole from heel to toe, thus providing for and facilitating the fitting of shoes to the wearer's foot in the securing of an accurate and proper fit.

It is of course essential to provide means whereby an accurate fitting of shoes may be facilitated and without resorting to the X-ray method, which last mentioned method has been adjudged by many doctors to be injurious to the foot in many cases of continuous use, and the use of which in certain places for the purposes in question having been prohibited.

Particularly is it essential in the case of shoes for children, and during the growth of the child's foot, to first provide for an accurate and proper fitting, and especially following such fitting to permit ready and adequate inspection of the child's foot and its relation to the shoe during such period of growth in determining when the shoe should be replaced to provide a proper fit.

Such being the general purpose of the invention, the main object thereof is to provide a shoe having a one-piece upper and a tongue and toe-cap portion therefor adapted to be fitted to the wearer's foot in the usual manner, and with the shoe so formed, when considering the shape of the upper and its attached tongue and toe-cap portion, that the tongue and toe-cap portion may be displaced from its normal position as assumed when the shoe is on the wearer's foot and laced for wear, to a position with respect to the upper where the entire insole of the shoe up to and including the extreme toe portion of said insole may be seen and inspected, thereby further permitting the position of the wearer's foot with respect to the insole to be observed and with the foot in place in the shoe.

A further and most important object of the invention is the provision of a visible gauge marking upon the upper face of the insole at the toe portion thereof, said marking to indicate the size of the shoe and the proper position to be assumed by the toe portion of the foot with respect to the insole when the shoe is applied to the foot, and further serving as an indication to be watched from time to time during the growth of a child's foot to show the mother when the shoe should be replaced to provide for proper wearing conditions.

The above and other features of the present

2

invention will be further understood from the following description when read in connection with the accompanying drawing illustrating a practical embodiment of the invention.

In the drawing:

Figure 1 is a perspective view of a shoe embodying the features of the present invention.

Figure 2 is a top plan view of the shoe as it would appear in laced condition; and

Figure 3 is a top plan view of the shoe showing the tongue extended outwardly to expose the entire shoe insole and its visible gauge marking, and further showing the wearer's foot therein indicated by broken lines.

10 Referring to the drawings, 10 designates a one-piece upper which is seamless except for the seam at the back or counter portion of the shoe (which seam is covered by a counter pocket or lining), thus providing a shoe where no seams are exposed to the wearer's foot. Attached to the upper, preferably as an integral part thereof, is a tongue or strip 11 provided for closing the gap in the front of a laced or similar type of shoe where it serves as a covering for the instep and toe portion of the wearer's foot, and it is to be particularly noted that the tongue portion or strip 11 is connected to and extends from the top edge of the extreme substantially vertical portion 12 of the toe-portion of said shoe upper and at a point directly above the extreme forward toe-portion of the shoe insole, thus permitting the tongue or strip 11 to be moved in an outward direction and away from its normal instep and toe covering position with respect to the upper and to be so positioned as to permit inspection of the entire insole of the shoe up to and including the extreme toe-portion thereof, and furthermore allowing the wearer's foot to be observed, including the toe-portion thereof, when 20 the shoe is upon the foot. Thus it is possible to watch the development of the foot from time to time and its particular relation with respect to the shoe, or in other words, one can actually look inside the shoe up to and including the extreme toe-portion of the insole.

25 In the embodiment of the invention disclosed by the drawing, the tongue portion of the shoe 11 is integrally formed with the upper, and there is a relatively narrow connecting neck portion 30 13 between the upper proper and said tongue, which connecting neck portion 13 extends from the top part of the extreme vertical portion 12 of the toe portion of the shoe upper, and as stated herein, extends from a point directly above the 35 extreme toe-portion of the shoe insole, and for

the purposes as indicated herein. Furthermore, said tongue from the connecting neck portion 13 to its free end is of increased width and this, as is obvious, to provide for the covering of the instep and toe portion of the wearer's foot and furthermore to permit the side edges of said tongue to be overlapped by the upper when the shoe is laced or otherwise secured to the wearer's foot and in the usual manner.

Referring now to the shoe insole, which, as noted can be observed, when necessary, throughout its entire extent, provision has been made for applying to the top face of the insole near the extreme toe-portion thereof, a visible gauge line or marking 14 to indicate a point beyond which the toe-portion of a foot should not be placed with respect to the insole, if proper fit is to be had. It being possible to observe the entire insole from heel to toe, as above indicated, the marking, which may be called a "growth line," is of course clearly visible to serve as a gauge to be used for determining when the shoe is too short for any particular wearer's foot, and furthermore, may be consulted from time to time during normal growth of the foot and act as a warning as to time for replacement with a shoe of proper size.

This "growth line" or marking may be in the form of a line or a spot, or in fact any visible indication for permanently marking the size of the shoe.

It will be apparent from the foregoing that a shoe constructed in accordance with the present invention renders it possible to properly fit the shoe to a wearer's foot without the use of the X-ray method, and furthermore greatly facilitates such fitting when realizing that it is possible to observe the entire toe-portion of the wearer's foot when in place within the shoe and also the position assumed by the foot with respect to the shoe insole and its visible gauge marking which indicates the size of the shoe.

Modifications of this invention may be used without departing from the spirit thereof or the scope of the claims, and therefore the exact form shown is to be taken as illustrative only and not in a limiting sense.

What we claim as new and useful and desire to secure by Letters Patent is:

1. In a shoe, an insole for said shoe, an upper for said shoe, said upper having a vamp with integral sides and toe-end portions, said vamp extending uninterruptedly around the toe-end of the upper and said toe-end being substantially vertical at the extreme forward end of said shoe, and a tongue and toe-cap portion for said upper connected to and extending hingedly from the top edge of said substantially vertical toe-end portion, said tongue and toe-cap portion being necked-in at its point of connection with the toe-end portion, whereby the tongue and toe-cap portion may be removed from its normal instep and toe covering position to thereby assume a position permitting visual inspection of the entire top face of the insole up to and including the extreme toe-portion thereof.

2. In a shoe made from opaque material, an insole for said shoe, an upper for said shoe, said upper having a vamp with integral sides and toe-end portions, said vamp extending uninterruptedly around the toe-end of the upper and said toe-end being substantially vertical at the extreme forward end of said shoe, a gauge marking upon the upper face of the insole and located at the forward toe portion of said insole,

and a tongue and toe-cap portion for said upper integrally connected to and extending hingedly from the top edge of said substantially vertical toe-end portion, said tongue and toe cap portion being necked-in at its point of connection with the toe-end portion, whereby the tongue and toe-cap portion may be removed from its instep and toe covering position and assume a position to thereby permit visual inspection of said gauge marking and its relation to the wearer's foot within the shoe.

3. In a shoe, an insole for said shoe, an upper for said shoe, said upper having a vamp with integral sides and toe-end portions, said vamp extending uninterruptedly around the toe-end of the upper and said toe-end being substantially vertical at the extreme forward end of said shoe, a tongue and toe-cap portion for said upper, and a relatively narrow necked-in portion at the top edge of said substantially vertical toe-end portion for connecting said tongue and toe-cap portion to said upper at the extreme forward end of said shoe, said narrow necked-in portion being centrally located at the top edge of said substantially vertical toe-end portion and serving as a hinge for the tongue and toe-cap portion, whereby the tongue and toe-cap portion may be removed from its instep and toe-covering position and assume a position to thereby permit inspection of the entire top face of the insole up to and including the extreme toe-portion thereof directly adjacent the inner wall of the substantially vertical toe-end portion.

4. In a shoe, an insole for said shoe, an upper for said shoe, said upper having a vamp with integral sides and toe-end portions and with the vamp sides including lacing flap portions, said vamp extending uninterruptedly around the toe-end of the upper and said toe-end being substantially vertical at the extreme forward end of said shoe, and a tongue and toe-cap portion for said upper connected to and extending hingedly from the top edge of said substantially vertical toe-end portion and when in its normal instep and toe covering position adapted to be overlapped by the lacing flap portions of the vamp, said tongue and toe-cap portion being necked-in at its point of connection with the toe-end portion, whereby the tongue and toe-cap portion may be removed from its normal instep and toe covering position to thereby assume a position permitting visual inspection of the entire top face of the insole up to and including the extreme toe-portion thereof.
